CAP DETECTOR FOR AUTOMATIC BOTTLE VENDING MACHINES

Noel M. Denison, Kansas City, Mo., assignor to
C. Earl Hovey, Kansas City, Mo., trustee

Application May 17, 1944, Serial No. 535,955

9 Claims. (Cl. 225—21)

This invention relates to vending machines for capped bottled goods, and has for its primary aim the provision of improvements to such equipment, and particularly that disclosed in U. S. Letters Patent No. 2,333,118 issued Nov. 2, 1943.

It is necessary in the satisfactory operation of vending machines for capped bottled goods, that the presence or absence of the conventional cap be detected before the bottle is passed to a decapping unit, especially where the movement of the bottle to said unit is based upon the introduction of a coin to the vending machine by the operator. In vending machines of the character shown in the aforesaid patent, the contents of the capped bottle is poured into a suitable receptacle, after the cap is automatically removed, therefore, if an empty, uncapped bottle is allowed to pass through the machine, the operator is deprived of the substance for which he has paid, and serious objections arise.

One of the important aims of this invention is the provision of means for detecting the presence of a bottle cap as the bottle is moved through a vending machine of the type disclosed in U. S. Letters Patent No. 2,333,118.

A yet further aim of this invention is to provide means for electrically determining the presence of a bottle cap, which means controls the further operation of the vending machine, to the end that the purchaser or the party presenting a coin to the vending machine, will not be deprived of the purchase price of the commodity which he intended to purchase, without having delivered the said commodity.

Further objects of the invention include the provision of a specially mounted magnet, elements for actuating a control switch when the mounting for the magnet has been shifted to a certain position, means for limiting the movement of the magnet and its supporting parts, and a unit for arresting and maintaining the bottle in a location adjacent to the magnet where the presence of a cap thereon will have the desired effect of shifting the magnet and its supporting elements and thereby actuating an electrical switch to control the further operation of the vending machine with which the cap detector is associated.

Other objects of the invention will appear during the course of the following specification, referring to the accompanying drawings, wherein:

Fig. 1 is a fragmentary side elevational view of a portion of a vending machine, illustrating the cap detector embodying the present invention.

Fig. 2 is an enlarged fragmentary sectional view through a portion of a vending machine, illustrating the cap detector in elevation.

Fig. 3 is a fragmentary vertical sectional view taken on line III—III of Fig. 2.

Fig. 4 is a fragmentary side elevational view of the bottle elevating and decapping equipment, showing the bottle in the many positions assumed as the same is raised from the point of rest shown in Fig. 1; and

Fig. 5 is a wiring diagram of the electrical circuit of the machine wherein the cap detector embodying this invention is interposed.

The cap detector disclosed as a part of the vending machine shown in the above identified patent is practical and operable unless concentric caps are encountered, whereupon the weight impressed upon the control switch is reduced and in some instances, the cap fails entirely to approach the switch and operate the same.

In the vending machine covered by the patent, it is desirable to arrest the movement of the bottle if no cap is present, which of course, indicates that there is nothing in the bottle to be poured therefrom.

In machines of the type to which this invention refers, it is necessary to provide positive means for detecting the presence of a cap for there is usually no attendant close by and if a deformed cap should present itself for detection, the machine would stop if the apparatus was not sufficiently versatile to detect the deformed cap and allow the bottle to proceed. The detector about to be described, therefore, is usable in vending machines where bottles having metallic caps are handled and the apparatus for shifting or handling the bottles is accomplished through electrically driven means. The detector includes primarily a magnet for maintaining the electrically driven apparatus operative only when a capped bottle has been disposed in the field of the magnet, as more fully set down herein-after.

The mechanical parts for manipulating the bottle are here collectively and generally designated by the numeral 10, and the bottle is indicated by the numeral 12.

Switch 14 having conductors 16 and 18 are analogous to parts 94, 270 and 272 of Patent No. 2,333,118. As described in that patent, it is necessary for switch 14 to be closed before the machine can operate to move the bottle beyond the position which it has assumed just prior to having the cap removed. Bottle 12 is shown in that position in Fig. 1 in the drawings, and

the metallic cap 20 lies in the field of magnet 22 when the bottle is in the position illustrated with the neck thereof resting in support 24. The bottle moves to the position illustrated from a portion of the machine 10, and is travelling in the direction of the arrow shown in Fig. 2, just prior to its being arrested in its movement.

When the bottle is lying in support 24, the presence of a metallic cap 20 will draw magnet 22 to the position illustrated in dotted lines in Fig. 2. Normally, magnet 22 is in the position illustrated in full lines and its swingable support will not be exerting pressure upon finger 26 of switch 14.

The swingable support is in the nature of a lever 28, pivotally mounted as at 30, and formed substantially as shown in Fig. 2. The formation of this lever 28 requires only that when magnet and lever 22 and 28 respectively are in the normal position shown in full lines of Fig. 2, that finger 26 be free and in a place where the contact points of switch 14 are not closed. A stop 32 limits the movement of lever 28 in one direction and it is against this stop that the lever rests when the action of gravity maintains the magnet and lever in a set condition, ready for movement by the presence of a bottle cap 20.

When a metallic bottle cap 20 drops into support 24, lever 28 will move about its pivotal support 30 to the position shown in dotted lines of Fig. 2, due to the magnetic attraction between the metallic cap 20 and magnet 22. Thus, the contact points of switch 14 will be closed and the vending machine will thereafter continue its operation by moving the bottle to a decapper, pouring the contents of the bottle into a receptacle, and thereafter depositing the emptied bottle in a magazine, all as set down in the above identified patent.

When bottle 12 is pulled away from magnet 22, the tendency to further swing lever 28 is overcome by stop 34, which absorbs the pull on magnet 22 due to the movement of cap 20, and thereby relieve any destructive tendency that lever 28 may have upon finger 26.

The metallic cap need have no particular form to be detected by the apparatus hereinabove described, and therefore, positive action is insured without regard to contour of the cap, the presence of which is to be detected, and the nature of which is such as to be receivable by the decapping portion of the vending machine 10.

When the machine, having the cap detector made as above set forth, is loaded and set, a capped bottle 12 is positioned in cradle 84 and as the bottles are elevated towards the decapper 122 by motor 168, another bottle 12 immediately moves to place.

The operation of the decapper is clearly set forth in the patent above identified, and the tilting action is such that cap 20 of bottle 12 is engaged by decapper 122, as illustrated in dotted lines of Fig. 4.

This decapper is assisted in its operation upon cap 20 by guides 124 that insure centering of the bottle as it is tilted. Decapper 122 is pivotally mounted on shaft 121, carried by the end of the cabinet, which houses the parts 10 of the vending machine.

Spring 126 yieldably maintains the decapper in the position shown in full lines of Fig. 4. One leg 123 of decapper 122 is bifurcated to straddle the neck of the bottle immediately below cap 20 to insure an even pull on each side thereof. Bottle 12 is moved longitudinally in a straight

line against decapper 122 to rotate the latter about its mounting—thus, the cap is forced against hump 125 on leg 127 and is pried from place.

5 A conventional cup feeding mechanism 128 is operably joined to decapper 122 through the medium of a cable 130 and arm 132. This cup dropping mechanism 128 is obtainable on the open market and further description thereof is unnecessary. When the containers 134 are fed from 128, they are dropped by gravity to shelf 136. Cup shelf 136 is specially made with weight operated switches forming a part of the circuit shown in Fig. 5.

10 After cap 20 is withdrawn from bottle 12, the continued upward movement of cradle 84 tilts the bottle to a downwardly inclined position shown in the uppermost dotted lines of Fig. 4, where the contents of the bottle is poured into container 134. During the decapping operation roller 98 bears against block 140 to insure rigidity and the same roller is positioned adjacent the inclined face of member 142 during the pouring operation.

15 After cap 20 is withdrawn from bottle 12, the continued upward movement of cradle 84 tilts the bottle to a downwardly inclined position shown in the uppermost dotted lines of Fig. 4, where the contents of the bottle is poured into container 134. During the decapping operation roller 98 bears against block 140 to insure rigidity and the same roller is positioned adjacent the inclined face of member 142 during the pouring operation.

20 The electrically operated means for moving the bottle is motor 168 having its shaft 172 operably joined to rack 66 through a pinion, and so long as motor 168 operates in either direction, rack 66 will move to motivate cradle 84.

25 The electrical circuit illustrated in Fig. 5, forms a part of the vending machine disclosed by U. S. Letters Patent No. 2,333,118. The switch which is maintained closed by the bottle cap in the said patent, depends upon the weight of the bottle when a cap is present to hold the switch points together. Since the switch embodying my present invention performs in a similar fashion, an understanding of the electrical circuit shown in Fig. 5, with switch 14 therein, will suffice.

30 The electrical circuit employed permits automatic operation of the machine upon depositing a coin or token therein. A conventional coin switch 202 is closed by the dropping of a coin and when the terminals of the switch are closed, the machine will operate if a capped bottle 12 is in the position shown in Figs. 1 and 2.

35 When a coin is dropped, switch 202 is closed and energy is supplied to motor controlled relay bank 222 through a circuit including my cap detector switch 14, which, if a capped bottle is present, is held closed as shown in dotted lines of Fig. 2. If no cap is present, the machine will not operate but the coin will be returned to the depositor. If the switch 14 is closed and a coin is dropped to close switch 202, the circuit is completed as follows:

40 From power line 256 through wire 260, wire 262, one closed arm of switch 246, wire 264, forward relay coil 266, wire 268, closed coin switch 202, wire 16, closed switch 14, wire 18, wire 274, wire 276, the other closed arm of switch 246, and wire 278 to power line 258. When this circuit is closed momentarily by a coin, coil 266 is energized to close contact points 280 and 282 of the forward relay in control 222. Immediately following the closing of points 280 and 282, the coin will drop from the coin controlled switch, whereupon coil 266 is maintained energized through the following circuit:

45 Line 256, wire 260, wire 262, one closed arm of switch 246, wire 264, coil 266, contacts 280 and 282, wire 284, wire 274, wire 276, other closed arm of switch 246, and wire 278 to line 258.

50 When coil 266 closes points 280 and 282 it also closes contact points 286 and 288, 290 and 292,

and 294 and 296. When these points are closed, the motor 168 receives current through the following circuit:

From line 256 through wire 260, wire 298, wire 300, wire 302, closed contacts 292 and 290, wire 304, wire 306 to terminal 2 of motor 168. The internal circuit of motor 168 connects terminals 2 and 1. Current then passes through wire 322, wire 324, closed contacts 296 and 294, wire 326, wire 328 to terminal 3. Internal circuit of motor 168 connects terminals 3 and 4. From motor 168 through terminal 4, wire 308, wire 310, closed contacts 288 and 286, wire 312, wire 314, closed side of switch 224, wire 316, wire 318, closed side of switch 226, wire 320, wire 276, switch 246, wire 278 to line 258.

As the motor 168 elevates rack 66, bottle 12 is decapped, container 134 is deposited on platform 232 of shelf 136, and the contents of bottle 12 is poured into container 134. Rack 66 continues to rise and deposit bottle 12—all as described in the aforesaid patent, whereupon the motor reverses and rack 66 returns to the point of beginning. When the filled cup 134 is removed from platform 232, motor 168 is started to return the bottle gripping and elevating means to the position shown in Fig. 1.

When rack 66 reaches its lowermost point, the arm of switch 24 is engaged to again set up the circuit for actuating the machine when a coin is again dropped.

As the rack 66 approaches the lowermost position the last portion of its travel is employed to feed another capped bottle 12, whereupon switch 14 will be closed, if the bottle has a cap 20 thereon and again the machine may start when a coin is dropped, as just set down.

A more detailed description of the circuit shown in Fig. 5 is unnecessary because of the complete manner in which it is disclosed in the patent above identified.

Having thus described the invention, what is claimed as new and desired to be secured by Letters Patent is:

1. In a vending machine for bottles normally having metallic caps, said machine including electrically operated means for moving the bottles, means for detecting the presence of caps on the bottles as they pass a given point, one at a time in their movement and for controlling the further operation of the machine, comprising a switch in the circuit of the electrically operated means; and parts to open and close the switch including a magnet shiftable to a position to actuate the switch when a capped bottle appears at said given point.

2. In a vending machine for bottles normally having metallic caps, said machine including electrically operated means for moving the bottles, means for detecting the presence of caps on the bottles as they pass a given point, one at a time in their movement and for controlling the further operation of the machine, comprising a switch in the circuit of the electrically operated means; and parts to open and close the switch including a magnet shiftable to a position to actuate the switch when a capped bottle appears at said given point, said parts being adapted to automatically return to their normal positions when the capped bottle is carried from said given point.

3. In a vending machine for bottles normally having metallic caps, said machine including electrically operated means for moving the bottles, means for detecting the presence of caps on the

bottles as they pass a given point, one at a time in their movement and for controlling the further operation of the machine, comprising a switch in the circuit of the electrically operated means; and parts to open and close the switch including a magnet shiftable to a position to actuate the switch when a capped bottle appears at said given point, certain of said parts being held against the cap of the bottle as the capped bottle is in position at said given point.

4. In a vending machine for bottles normally having metallic caps, said machine including electrically operated means for moving the bottles, means for detecting the presence of caps on the bottles as they pass a given point, one at a time in their movement and for controlling the further operation of the machine, comprising a switch in the circuit of the electrically operated means; parts to open and close the switch including a magnet shiftable to a position to actuate the switch when a capped bottle appears at said given point; and a cradle at the said given point to arrest the bottle in place therat.

5. In a vending machine for bottles normally having metallic caps, said machine including electrically operated means for moving the bottles, means for detecting the presence of caps on the bottles as they pass a given point, one at a time in their movement and for controlling the further operation of the machine, comprising a switch in the circuit of the electrically operated means; and parts to open and close the switch including a magnet shiftable to a position to actuate the switch when a capped bottle appears at said given point, said parts being movable through a given path of travel, the bottle cap being in a location when at a given point to stop the movement of the parts before they reach the end of their path of travel in one direction.

6. In a vending machine for capped bottles, a rack for supporting the bottles; means for moving the bottles into a discharged position; apparatus for decapping and pouring the contents of the bottle into a suitable container; and means for rendering inoperative the decapping and pouring apparatus when an uncapped bottle is fed into the discharged position, said last mentioned means including a magnet movable to the operative position by the cap of a discharged bottle to render operative portions of the decapping and pouring apparatus.

7. In a vending machine for capped bottles, a rack for supporting the bottles; means for moving the bottles into a discharged position; apparatus for decapping and pouring the contents of the bottle into a suitable container; and means for rendering inoperative the decapping and pouring apparatus when an uncapped bottle is fed into the discharged position, said last mentioned means including a magnet movable to the operative position by the cap of a discharged bottle to render operative portions of the decapping and pouring apparatus, said magnet being immovably maintained in place when an uncapped bottle is fed into the discharged position.

8. In a vending machine for bottles normally having metallic caps, said machine including electrically operated means for moving and decapping the bottles, means for detecting the presence of caps on the bottles as they assume a position in the machine and for rendering the electrically operated means inoperative upon the presence of an uncapped bottle, said means comprising a switch having separable contact points in the circuit of the electrically operated means,

a pivoted lever for opening and closing the contact points; a magnet on the lever; and a support formed to hold the mouth of a bottle in the field of the magnet, said contact points being closed when a capped bottle is in the support with the magnet against the cap thereof.

9. In a vending machine for bottles normally

having metallic caps, and apparatus for shifting bottles within the machine, means including a magnet for rendering the apparatus operative at the beginning of its cycle of operation only when a capped bottle is within the field of the magnet.

NOEL M. DENISON.
